DESIGN FOR AN END CAP FOR A FLUORESCENT LIGHTING FIXTURE

David J. Biller, St. Louis, Mo., assignor to Day-Brite Lighting, Inc., St. Louis, Mo., a corporation of Missouri

Application November 17, 1944, Serial No. 116,407

Term of patent 14 years

(Cl. D48—23)

To all whom it may concern:

Be it known that I, David J. Biller, a citizen of the United States and a resident of the city of St. Louis and State of Missouri, have invented a new, original, and ornamental Design for an End Cap for a Fluorescent Lighting Fixture, of which the following is a specification, reference being had to the accompanying drawing, forming part thereof.

Fig. 1 is a front elevational view of an end cap for a fluorescent lighting fixture, showing my new design,

Fig. 2 is an end elevational view thereof, Figs. 3 and 4 are vertical cross-sectional views on the lines 3—3 and 4—4, respectively, in Fig. 1, Fig. 5 is a top plan view of said end cap; and Fig. 6 is a bottom plan view thereof.

I claim:

The ornamental design for an end cap for a fluorescent lighting fixture, as shown.

DAVID J. BILLER.
